UNITED STATES PATENT OFFICE.

WILLIS S. CRANDELL, OF ELSMERE, NEW YORK, ASSIGNOR TO ALBANY PERFORATED WRAPPING PAPER COMPANY, OF ALBANY, NEW YORK, A CORPORATION OF NEW YORK.

MACHINE FOR AND PROCESS OF PRODUCING ROLLS OF PAPER FOR TOWELS, TOILET PAPER, ETC.

Original application filed December 16, 1918, Serial No. 266,862. Divided and this application filed July 10, 1920. Serial No. 395,276.

To all whom it may concern:

Be it known that I, WILLIS S. CRANDELL, a citizen of the United States, residing at Elsmere, in the county of Albany and State 5 of New York, have invented a certain new and useful Machine for and Process of Producing Rolls of Paper for Towels, Toilet Paper, Etc., of which the following is a specification.

10 My invention relates to a machine for and process of producing rolls of paper for towels, toilet paper, etc.

The object of my invention is to provide a process of and a machine for winding rolls 15 of paper towels, toilet paper, etc., which shall have the advantages, among others, of forming or winding the rolls without breakage of the web of paper from which said rolls are formed, and of providing a machine 20 which is simple and readily operated and adjusted.

The present application is a division of a prior application, Serial Number 266,862, filed by me on December 16, 1918.

25 My invention in the process is capable of being performed by mechanical means of many different forms and my invention in the machine is capable of embodiment in many different forms. While, therefore, 30 I shall illustrate my invention by the best embodiment known to me, such embodiment is to be regarded only as typical of many possible embodiments, and my invention is not to be confined thereto.

35 In the manufacture of rolls of paper towels and toilet paper, it is customary to wind the roll of paper coming from the paper-forming machine into a large roll called a "jumbo roll," from which rolls that 40 are usually both smaller in diameter and narrower in width are to be formed, to make rolls of towels or of toilet paper. My invention relates to a process and machine for making the latter type of rolls.

45 Fig. 1 is a rear elevation, with certain parts broken away, of the illustrative machine;

Fig. 2 is a side elevation thereof, looking toward the right hand side as viewed in 50 Fig. 1;

Fig. 3 is an elevation of the side opposite to that shown in Fig. 2 and partly in section taken on the line 3—3 of Fig. 1;

Fig. 4 is a detail vertical section taken on the line 4—4 of Fig. 3, showing the means 55 for adjusting the slideway of the stock-roll carriage;

Fig. 5 is a vertical section taken on the line 5—5 of Fig. 1, looking in the direction of the arrows;

Fig. 6 is an enlarged fragmentary detail in section taken on the line 6—6 of Fig. 1, looking in the direction of the arrows;

Fig. 7 is a detail vertical longitudinal section taken on the line 7—7 of Fig. 6, looking in the direction of the arrows;

Figs. 8 and 9 are detail plan views, partly in section, of the rewinding shaft with the adjacent co-operating parts.

My process and the principal operative 70 parts of the machine which I have selected as one means of performing the process will first be explained in outline (by reference to Figs. 1 and 6), after which the explanation in detail will be more easily understood. In the said figures, the web 1 is shown as led from a jumbo roll 2 (having an axle 3), preferably over a pinch roll 4 to the surface of a drum 5, around the periphery of which the web travels, the web 80 being wound upon a rewinding shaft 6 to form a rewound roll 7 of towels or toilet paper. In its passage around the drum 5, the web is preferably cut transversely (but not completely severed), by serrating knives 85

8 carried by a serrating roll 9, which knives are received in grooves 10 in the drum 5. A second pinch roll 11 is preferably provided on the opposite side of the drum 5 from the pinch roll 4, said rolls serving to hold the web against the surface of the drum and the first pinch roll also serving to support the web in its passage from the jumbo roll to the winding drum. The paper wound upon the rewinding shaft 6 is severed 90 longitudinally by annular knives or cutter discs 12 carried by a slitting roll 13. The slitting roll is driven at a faster surface speed than the winding drum and, therefore, tends to roll the paper tightly upon the re- 100

winding shaft, and thus tends to make a relatively small, compact roll of a given length of paper web.

Taking up now the detailed description 5 of the machine and the process practiced thereby:—

In the said machine there are side frames 14 on which are mounted the bearings of the various rolls beforementioned. The axle of 10 the jumbo roll is laid in open bearings 15 formed on carriages 16, each of which is supported by a pair of rollers 17 on a way 18. Each way is pivoted, preferably at its rearward end, on a fulcrum 19 mounted on 15 one of the side frames so that the forward end of the way can be raised to cause the carriage to tend to roll toward the winding drum. Each way is preferably provided with an arm or other projection (which in 20 the present instance is in the form of a sector 20) which, by an adjustable connection with the side frame can be made to support the way at any desired inclination. In the present instance I have shown the said sector 25 as provided with a curved slot 21 through which passes a bolt 22 that is fastened in the side frame. A threaded rod 23 is secured on said bolt by an eye 23^a, the said rod itself passing through a hole in an ear 24 formed 30 on the said segment, and a hand nut 25 being threaded upon the said rod and supporting the said ear thereon. By turning the hand nut, the ear, and with it the segment and ways, can be raised or lowered. In the present 35 instance each carriage is provided with ribs or flanges 16^a which project into grooves formed in the ways, and thus the carriages are prevented from rising off the ways.

As a further means for causing the jumbo 40 roll to tend to move toward the winding roll, a chain or other form of flexible connection 26 is attached to each carriage and is passed rearward (toward the winding drum) and around a guide pulley 27, and thence forward and around another guide pulley 28 from which the chain hangs vertically, and supports a weight. By using a proper inclination of the ways or a suitable weight 29, or both, the jumbo roll can be forced toward 45 the drum so that it will always be in contact either with the pinch roll 4 or with the drum, if, as might be done, the pinch roll were omitted. As the diameter of the jumbo roll decreases, its axle is moved forward so 50 that its periphery is always in contact with the pinch roll or the winding drum. This arrangement always affords uninterrupted support for the web in its travel from the jumbo roll to the winding drum and thus eliminates a frequent cause of breakage of the web. The winding drum 5 is mounted in stationary bearings in the side frames, and in the illustrated embodiment of my invention it carries a driving pulley 30 by 55 which the entire machine is driven. Pinch 60 rolls 4 and 11 are each so mounted as to be movable toward and from the winding drum to maintain a constant pressure against the winding drum notwithstanding any possible variations in the periphery of the said drum 70 or in the thickness of the web of paper to be wound, and the said pinch rolls are preferably yieldingly pressed against the winding drum. In the present instance the pinch rolls are journalled in the upper ends of 75 arms 31 which are fulcrumed on pins 32 that are supported by the side frames, and each arm is yieldingly pressed toward the winding drum by a spring 33 mounted on a bolt 34 which passes through an opening in the 80 said arm and through a flange or web on the side frame, a nut 34^a on the said bolt resting against the said flange and serving to adjust the pressure of the spring against the arm. The serrating roll 9 is journalled in the side 85 frames below the drum 5 from which it is driven by gears 35 and 36 mounted on the axles of said rolls. The serrating roll is, in the present instance, shown as provided with three serrated knives 37 having saw-tooth 90 edges, which knives enter the grooves 10 on the winding drum and partly but not wholly sever the web of paper transversely. The pinch rolls, by holding the web tightly against the surface of the drum, and the 95 slitting roll 13, by travelling at a faster surface speed than the winding drum, hold the web tight across the grooves so that it resists the tendency of the serrating knives to push it into the grooves and causes a good cutting 100 action to take place. The rewinding shaft 6 simply lies upon the surface, preferably the upper surface of the drum, and preferably by having spring journals in its ends 105 extending between and held in place by two vertical ribs or splines, so that it can rise as the roll of paper wound upon it increases in diameter, but it is preferably not driven by power applied to it. The spring journals (shown in detail in Figs. 8 and 9) recede 110 into the end of the shaft when placed in the machine and pass through slots in the opposite spline when removed. The slitting roll 13 consists of a shaft 13^a upon which is threaded a series of rolls 13^b having the annular knives or cutter discs 12 between them. I desire to drive the slitting roll so that its surface speed shall be greater than that of the winding drum, and consequently so that 115 its action will be to tend to wind the roll being formed upon the rewinding shaft tightly to make a relatively hard and small roll, and I also desire to permit the slitting roll to recede from the rewinding roll as the diameter of the roll being formed increases. 120 For this purpose I mount the slitting roll in bearings formed in a vertical, slideable gate or frame consisting in the present instance of bars 38 (in the lower ends of which the 125 said shaft is journalled), which bars are 130

mounted in vertical guides formed in uprights 39 on the side frames, the said bars being connected by a brace 38^a in order to drive the slitting roll. The shaft of the said 5 roll is extended through a slot 39^a formed in one of the uprights 39, and the extended end of the shaft is, in the present instance, shown as journaled in a bearing supported by a bracket 40, which extends from the gate or 10 slide 38 around the upright into position to support the said bearing. The shaft 13^a of the slitting roll is provided with a sprocket wheel 41, and in order to drive the said wheel and yet permit the latter to move up 15 and down with the gate, I have provided the following arrangement: A sprocket chain 42 passes around a driving sprocket 43, that is frictionally secured upon the shaft 5^a of the winding drum, and around a guiding sprocket 44, journaled on a stud secured to 20 the upright 39. The frictional drive for the sprocket gear 43 is in the present instance shown as consisting of a hub 45 fixed on the said shaft and against which the sprocket 25 gear 43 rests, a preferably fibre disc 46 resting against the opposite face of the sprocket gear, and a split nut 47 threaded on the shaft 5^a and adapted to be secured in adjusted position by a screw 5^b by which the split can 30 be drawn together. Between the driving sprocket gear 43 and the guide pulley 44 the sprocket chain 42 passes over a sheave 47^a mounted on a plate 48, which latter also carries a flange 49 that is adapted to bear 35 against the side of the chain opposite the sprocket wheel 41 on the slitting roll shaft and to hold the chain so that the latter sprocket gear will always be in contact with it and be driven by it, no matter in what position toward or away from the winding 40 drum the slitting shaft may be. In order to keep the said adjustment and allow for wear, the plate 48 is adjustably mounted on the frame by being set against a vertical flange 45 or plate 39^b on the upright 39 to which flange the plate 48 is secured as by bolts 39^c in one of said parts and passing through slots in the other of said parts.

By this construction, the driving sprocket 50 gear 43, rotating with the shaft of the drum, tends to drive the slitting roll at a surface speed greater than that of the outermost layer of paper on the roll being formed, and the friction drive before described permits 55 the gear 43 to yield so that, while the paper on the roll being formed is put under tension and is rolled tightly, it is not torn. A relatively hard, compact and desirable roll is thus formed without breaking the paper.

It is in order that the slitting roll may be raised to permit the rewinding shaft 6 with 60 its rolls of paper thereon to be removed from the machine and the empty rewinding shaft replaced in the machine, that the slitting roll shaft has been mounted in the be-

fore-described gate or slide, and means have been provided for raising and lowering the latter. In the present instance the means consist of racks 50 formed on the bars 38, in which the slitting roll shaft is journaled, 70 pinions 51 mounted on a shaft 52 that is journaled on the uprights 39, and means for turning the said shaft. The latter means shown consist of a sheave 53 having a sprocket chain 54 wound thereon in such a 75 direction that the pull of the sprocket chain shall tend to raise the gate, while the weight of the gate shall tend to wind the sprocket chain up on the sheave. The sprocket chain 54 is shown as connected to a treadle 55 80 which is secured to a shaft 56 having a fixed bearing, which shaft carries an arm 57 upon which a weight 58 is adjustable, so that by adjusting the said weight the desired pressure of the slitting roll upon the rolls of 85 paper will result. The bearings of the shaft 52 are made adjustable so that the slitting roll can be adjusted to bear evenly on all the rolls being formed on the rewinding shaft. In the present instance the said bearings 59 90 are shown as adjustably secured to a vertical face of the uprights 39 and resting upon vertical screws 60, which pass through lugs 61 secured to the uprights.

It is to be observed that the roll 13 carrying the slitting knives 12 will itself normally be in peripheral contact with the roll of paper being formed upon the shaft 6, due to the fact that the knives 12 will cut through the web of paper, so that not only do the knives 95 100 105 110 115 120 125 130 135 140 145 150 155 160 165 170 175 180 185 190 195 198 200 205 210 215 220 225 230 235 240 trated embodiment of my invention: The shaft of the jumbo roll is laid in the bearings of the carriage 16 (and is preferably secured therein by means not necessary to describe), and the web of paper 1 is led over the pinch roll 4 and between the pinch roll and the drum 5, and then under the drum and between it and the serrating roll 9, and upward around the drum between the rear pinch roll 11 and the drum, and is then rolled around the rewinding shaft sufficiently to engage it therewith, all as shown particularly in Fig. 6. The gate which, during the latter operation, has been held elevated by pressure of the foot on the treadle 55, is allowed to descend until the slitting roll rests upon the rewinding roll. Gravity tends to cause the carriage 16 to slide down the ways 18 toward the drum 5, and this tendency is increased by the pull of the weights on the sprocket chains 26. Thus the jumbo roll is held against the pinch roll 4, and the latter serves to support the paper in its passage to the drum. The pinch rolls also hold the paper smoothly against the drum, preventing its wrinkling, the pressure of the springs 33 against the arms carrying the pinch rolls assisting. As the web passes around under the drum, it is serrated at proper intervals by the knives 37 carried by the serrating roll, which enter the grooves 10 in the drum, the paper being held tightly across the said grooves by the pinch rolls and by the pull of the slitting roll and the friction of the shaft of the jumbo roll, so that the serrating knives cleanly penetrate the paper instead of merely tucking it into the said grooves. The gearing for driving the slitting roll tends to drive it at a higher surface speed than that of the drum, so that said roll pulls the paper forward and winds it tighter around the rewinding shaft, as well as pressing the paper roll being formed between itself and the drum, and thus a relatively hard, compact roll is formed on the rewinding shaft, the yielding or friction drive of the slitting roll, however, preventing the slitting roll from tearing the paper. The slitting knives slit the web longitudinally so that instead of a single roll of the width of the paper, a number of separate rolls are formed on the rewinding shaft. The drive of the slitting roll shaft, consisting as it does of the sprocket wheel 41 engaging the vertical stretch of the sprocket chain 42, drives the slitting roll equally well, regardless of the fact that the increasing diameter of the roll being formed causes the slitting roll to rise. The driving gear of the slitting roll also causes a uniform pulling action of the surface of the slitting roll on the surface of the roll being formed, this pull not changing as the roll being formed increases in diameter. This is much simpler than any arrangement for driving the re-

winding shaft by gearing, since in the latter case it would be necessary to change the speed transmitted by the gearing as the diameter of the roll being driven increased. When the rolls being formed, however, reach the desired diameter, the web is severed, the slitting roll is raised by pressure on the treadle 55, and the rewinding shaft is lifted out of its vertical guides. The rolls which have been formed are then stripped off the rewinding shaft, and the web is again started around the rewinding shaft and the formation of new rolls is begun.

Among the advantages of my invention may be stated the following:

Throughout all of the steps of my process of forming a new roll, the web of paper is supported by continuous supporting surfaces in physical contact with the web, these supporting surfaces also having a peripheral movement equivalent to that of the advancing web of paper, and thereby, among other results, the liability of breakage is reduced to a minimum.

The illustrative machine here selected as one mechanical means of performing the process, is one of comparative simplicity.

In the machine, as the jumbo roll is, by the travel of the carriage, always kept in contact with the pinch roll, notwithstanding the constant decrease in diameter of the jumbo roll, such decrease in diameter does not result in any gap which the web has to span unsupported.

The pinch rolls tend to keep the paper smooth against the drum and prevent its wrinkling.

While the slitting roll can be raised and lowered to permit the rewinding shaft to be removed from and placed in the machine and to allow for increase of diameter of the rolls being formed, its driving mechanism is comparatively very simple.

The driving of the slitting roll at a faster surface speed than that of the drum results in a relatively hard and small roll being formed and by mechanism which is comparatively very simple, and yet the yielding drive for the slitting roll prevents breakage of the web being operated upon.

The stock or parent roll being always in contact with and driven by the nearer pinch roll or the drum, is driven at the same surface speed as the pinch roll or the drum and also at the same speed as the roll being formed, which not only prevents, to a considerable extent, breakage of the web, but also effects a considerable saving in the time required to stop and start the machine. If it were not for this contact drive, both the machine and the stock roll would have to be started and stopped slowly, as otherwise the web would be broken, due to the inertia of the stock or parent roll, and in stopping, the momentum of the latter roll would car-

ry it forward faster than the pinch roll or drum, and this would pile up the web and require that the stock or parent roll should be turned backward until the web 5 was just taut.

I claim:

1. The process of forming paper rolls, comprising unwinding a web from a large roll and rewinding it into a smaller roll 10 and maintaining a supporting surface in contact with the web substantially throughout the unwinding and winding processes so that the web is at all times supported.
2. The process of forming paper rolls, 15 comprising unwinding a web from a large roll and rewinding it into a smaller roll and maintaining contact between said large roll and the means for rewinding the web into a small roll.
3. In a roll-forming machine, the combination of means for forming a roll from a 20 web of paper, means for supporting a stock roll of such a web and means for maintaining contact between said stock roll and said 25 means for forming.

4. In a roll-forming machine, the combination of means for forming a roll from a web of paper, comprising a movable support for a stock roll, a drum which is adapted to have the web travel around the same, means for forming a new roll by rolling the web against the surface of said drum, a roll interposed between the stock roll and said 30 drum and which is adapted to carry the web, and means for maintaining the stock roll in contact with said last-mentioned roll.

5. In a roll-forming machine, the combination of a drum, means for guiding a web of paper thereto, a shaft upon which said 40 web is adapted to be wound, a roll adapted to bear upon the roll being formed and press it against said first-mentioned drum, and a slide in which said last-mentioned roll is journaled permitting movement thereof toward 45 and away from said first-mentioned drum.

6. In a roll-forming machine, the combination of a drum, means for guiding a web of paper thereto, a shaft upon which said 50 web is adapted to be wound, a roll adapted to bear upon the roll being formed and press it against said first-mentioned drum, a slide in which said last-mentioned roll is journaled permitting movement thereof toward 55 and away from said first-mentioned drum, and means for driving said last-mentioned roll comprising a sprocket wheel thereon, a sprocket chain, and means for guiding said chain parallel to the movement of said 60 sprocket wheel caused by said slide.

7. In a roll-forming machine, the combination of a drum, means for guiding a web of paper thereto, a shaft upon which said web is adapted to be wound, a roll adapted 65 to bear upon the roll being formed and press

it against said first-mentioned drum, a slide in which said last-mentioned roll is journaled permitting movement thereof toward and away from said first-mentioned drum, and means for yieldingly driving said last-mentioned roll comprising a sprocket wheel thereon, a sprocket chain and means for guiding said chain parallel to the movement of said sprocket wheel caused by said slide. 70

8. In a roll-forming machine, the combination of a drum, means for guiding a web of paper thereto, a shaft upon which said web is adapted to be wound, a roll adapted to press the roll being formed against said first-mentioned drum, a slide upon which said roll is mounted, and means for driving said roll comprising a sprocket chain therefor and an adjustable guide parallel to the line of movement of said slide and adapted to hold said chain against said sprocket 75 wheel. 80

9. In a roll-forming machine, the combination of a drum, means for guiding a web of paper thereto, a shaft upon which said web is adapted to be wound, a roll adapted to press the roll being formed against said first-mentioned drum, a slide upon which said roll is mounted, means for driving said roll comprising a sprocket chain therefor and an adjustable guide parallel to the line 90 of movement of said slide and adapted to hold said chain against said sprocket wheel, and means for driving said sprocket chain comprising a sprocket gear and a friction connection between said gear and said first-mentioned drum. 95

10. In a roll-forming machine, the combination of a drum, means for guiding a web of paper thereto, a shaft about which said web is adapted to be wound, a roll adapted to press the roll being formed against said first-mentioned drum, a slide upon which said pressing roll is mounted, and means adapted to raise said slide away 105 from said drum. 110

11. In a roll-forming machine, the combination of a drum, means for guiding a web of paper thereto, a shaft about which said web is adapted to be wound, a roll adapted to press the roll being formed against said first-mentioned drum, a slide upon which said pressing roll is mounted, and means adapted to raise said slide away from said drum, said means for raising comprising a rack on said slide, a pinion on the frame of the machine and engaging said rack, a sheave connected to said pinion, a chain on said sheave and a treadle to which said chain is connected. 115

12. In a roll-forming machine, the combination of a drum, means for guiding a web of paper thereto, a shaft about which said web is adapted to be wound, a roll adapted to press the roll being formed against said first-mentioned drum, a slide upon which 120 125 130

- 6 said pressing roll is mounted, and means adapted to raise said slide away from said drum, said means for raising comprising a rack on said slide, a pinion on the frame of 5 the machine and engaging said rack, a sheave connected to said pinion, a chain on said sheave, a treadle to which said chain is connected and an adjustable counter-weight connected with said treadle.
- 10 13. In a roll-forming machine, the combination of a rewinding mechanism, a carriage for a stock roll and guides for said carriage inclined in the direction of said rewinding mechanism, and maintaining the 15 stock roll in contact with a roll of the rewinding mechanism.
14. In a roll-forming machine, the combination of a rewinding mechanism, a carriage for a stock roll, guides for said carriage that are adapted to be inclined in the 20 direction of said mechanism, and means for inclining said guides, and maintaining the stock roll in contact with a roll of the rewinding mechanism.
- 25 15. In a roll-forming machine, the combination of a rewinding mechanism, a carriage for a stock roll, guides upon which said carriage is mounted, and means tending to force said carriage along said guides 30 in the direction of said mechanism.
16. In a roll-forming machine, the combination of a rewinding mechanism, a carriage for a stock roll, guides upon which said carriage is mounted, and means tending 35 to force said carriage along said guides in the direction of said mechanism, said last-mentioned means comprising a cable attached to said carriage and a weight attached to said cable.
- 40 17. In a roll-forming machine, the combination of a rewinding mechanism, a carriage for a stock roll, guides for said carriage pivoted so as to be adapted to be inclined toward said rewinding mechanism, 45 and means tending to force said carriage along said guides toward said rewinding mechanism.
18. In a roll-forming machine, the combination of a rewinding mechanism, a carriage 50 for a stock roll, guides for said carriage pivoted so as to be adapted to be inclined toward said rewinding mechanism, and means tending to force said carriage along said guides toward said rewinding mechanism, 55 said means comprising a cable attached to said carriage passing over a pulley and in a direction toward said rewinding mechanism and a weight on said cable.
- 60 19. In a roll-forming machine, the combination of means for supporting a stock roll, means for winding the web of the stock roll into smaller rolls and means for driving both of said rolls by contact of an intermediate roll with their surfaces.
- 65 20. In a roll-forming machine, the combination of means for supporting a stock roll, means for winding the web of the stock roll into smaller rolls and means for driving both of said rolls by contact of an intermediate roll with their surfaces, said rolls being driven at the same surface speed. 70
21. In a roll-forming machine, the combination of means for supporting a stock roll, means for forming smaller rolls from the 75 web of said stock roll, a roll or rolls adapted to drive said paper rolls at the same surface speed, and means for maintaining the stock roll in contact with one of said last-mentioned rolls.
22. The process of forming rolls, comprising unwinding a web from a large roll, rewinding it into smaller rolls, and driving the large roll by contact of an intermediate 80 roll with its surface.
23. In a roll-forming machine, the combination of means for supporting a stock roll, means for forming a smaller roll out of the web of said stock roll, and a roll or rolls contacting with said rolls of paper and driving 85 them at the same surface speed.
24. In a roll-forming machine, the combination of means for supporting a stock roll, means for forming smaller rolls from the web of the stock roll and a roll or rolls adapted to drive and maintain the periphery of the 90 stock roll in contact therewith.
25. The process of forming paper rolls, comprising unwinding a web from a large roll, rewinding it into smaller rolls and driving the large or parent roll by contact with the periphery of a driving roll, and maintaining said driving roll in contact with said 95 means for rewinding.
26. In a roll-forming machine, the combination of means for supporting a stock roll, means for winding the web of the stock roll into a smaller roll, and intermediate guide and driving rolls contacting respectively with the stock roll and the said smaller roll 100 to drive them by direct contact.
27. In a roll-forming machine, the combination of a forming roll, a guide roll spring-pressed into engagement therewith, and a stock roll yieldingly held in contact with 105 said guide roll, said guide and stock rolls being driven from said forming roll by peripheral contact.
28. In a roll-forming machine, the combination of a stock roll, a guide roll, a forming 110 roll and a rewinding shaft, arranged to present each with another contacting cylindrical surface.
29. In a roll-forming machine, the combination of a stock roll, a guide roll, a forming 115 roll and a rewinding shaft, arranged to present throughout said parts a continuous and uninterrupted cylindrical supporting surfaces for the paper web.
30. In a roll-forming machine, a forming 120

- roll and means for rotating the same, a rewind shaft yieldingly held in contact with said forming roll and adapted to be rotated by frictional contact therewith to form the 5 rewound roll of paper upon said rewind shaft, a guide roll for the paper web held in yielding contact with said forming roll, and a stock roll held in yielding contact with said guide roll.
- 10 31. The process of forming a roll of paper, comprising advancing a web of paper from a stock roll over the cylindrical surface of a guide roll in a direction of wind opposite to the winding on the stock roll and at the same 15 time maintaining the stock roll in peripheral contact with said cylindrical surface of said guide roll, maintaining said cylindrical surface of said guide roll in peripheral contact with a forming roll and advancing said web 20 from said guide roll over said forming roll in a direction of wind opposite to the direction of wind on said guide roll, forming the advancing end of said web into a new roll by a rolling motion of the same upon the cylindrical periphery of said forming roll.
32. The process of forming a roll of paper, comprising supporting the web of paper from a stock roll in continuous contact with the cylindrical surfaces of a plurality of rolls 30 in a series and forming the free end of said web into a new roll by a rolling motion of the same upon the cylindrical peripheral surface of the last roll of said series.
33. The process of forming a roll of paper, 35 comprising supporting the web of paper from a stock roll in continuous contact with the
- cylindrical surfaces of a plurality of rolls in a series beginning with the stock roll, advancing said web by a rotation of one of said rolls, and forming the advancing end of said 40 web into a new roll by a rolling motion of the same upon the cylindrical peripheral surface of the last roll of the series.
34. In a roll-forming machine, the combination of a drum, means for guiding a web of 45 paper thereto, a shaft about which said web is adapted to be wound, a roll adapted to press the roll being formed against said first-mentioned drum, and means to adjust the pressing roll to different positions in and out 50 of parallelism with the roll being formed.
35. In a roll-forming machine, the combination of a drum, means for guiding a web of paper thereto, a shaft about which said web is adapted to be wound, a roll adapted to 55 press the roll being formed against said first-mentioned drum, said pressing roll yieldingly mounted to move in a single plane radially of said roll being formed, and means to adjust said pressing roll in said plane to 60 different positions of its axis relative to the axis of said shaft.
36. In a roll-forming machine, a stock roll, a guide roll, a forming roll and a re-winding shaft arranged in a series, means 65 for yieldingly pressing said rolls into contact of their cylindrical surfaces, each with an adjacent roll throughout the series.

In testimony that I claim the foregoing, I have hereunto set my hand this 26th day of 70 June, 1920.

WILLIS S. CRANDELL.
